UNITED STATES PATENT OFFICE.

RICHARD W. JEFFERIS, OF CAMDEN, NEW JERSEY.

METALLIC SHELVING.

No. 917,870.

Specification of Letters Patent.

Patented April 13, 1909.

Application filed July 14, 1908. Serial No. 443,435.

To all whom it may concern:

Be it known that I, RICHARD W. JEFFERIS, a citizen of the United States, residing at Camden, in the county of Camden and State 5 of New Jersey, have invented certain new and useful Improvements in Metallic Shelving, of which the following is a specification.

My invention relates to metallic structures, and particularly to shelving and the 10 supporting frame therefor, the object being to provide metallic shelving built up of units or sections which is simple in construction, neat in appearance, and which yet may be easily set up or knocked down when de- 15 sired.

Another object is to provide shelves adjustable within the supporting frame or casing.

The invention consists in the arrangement 20 of parts and details of construction set forth particularly in the appended claims.

In the accompanying drawing Figure 1, is a face view of a shelving formed of two conjoined sections. Fig. 2, is an enlarged 25 transverse section thereof on line $x-x$ of Fig. 1. Fig. 3, is an enlarged vertical section on line $y-y$ of Fig. 1. Fig. 4, is an enlarged perspective view of one of the corner channel bars, and Fig. 5, is a perspective 30 view of one of the shelves detached.

Like reference characters throughout the several views designate like parts.

My metallic shelving is so designed as to provide a series of simple elements which 35 may be easily combined either to form a unit or number of units as desired, and to this end I provide each section with vertical corner pieces located at the four corners of the structure, all of like character, and connected by thin webs or plates of sheet metal.

In the drawings I have shown a set of shelving built up of two unit sections, a corner piece of which is shown in detail in Fig. 4. Each corner piece consists of a channel 45 bar 2 having the usual lateral flanges $2', 2''$, from one of which projects at right angles the flange $2'''$ parallel to the main web 2 of the channel bar. The flange $2'''$ is perforated along its length as will be later explained.

From Fig. 2, it will be seen that each unit

or section has a channel bar 2 at each corner with the flanges thereof extending inwardly. Connecting the front upright channel bars with the rear bars are the end or partition plates 3, 3'. These may be bolted or riveted either to the outside or the inside of the flanges $2'$ by bolts $3''$ as desired. The rear channel bars are connected by a back plate 55 or web 4. The lateral margins of this back plate are bent at right angles to the web 4 as at $4'$, and then extended laterally again as at $4''$. This construction offsets the lateral margins of the back plate. The margins $4''$ lie against the face of the rear 60 channel bars 2 and are bolted thereto by the bolts 5. It will be seen from Fig. 2 that the offset margin $4''$ of the back plate and the inwardly turned edge $2''$ of the channel bar provide a vertically extending compartment 65 14 immediately back of the flange $2'''$ at the back of the set of shelving.

There are of course as many shelves as may be desired. Each consists of a plate 6 of sheet metal having downwardly turned 70 edges $6'$. The front edge $6'$ of each shelf is provided with openings $6''$ at each end for the passage of bolts 7 which pass through perforations 10 in the flanges $2'''$ of the front channel bars. The rear flange 75 $6'$ of the shelf is also provided with openings of the same character as openings $6''$ through which pins 8 pass. These pins are each provided with an enlarged head $8'$ preferably attached to the under side of the 80 shelf as shown in Fig. 3; and supporting the same. This pin projects through any one of the series of perforations 10 in flanges $2'''$ of the rear channel bars. These perforations correspond with the like series of 85 perforations 10 in the flanges $2'''$ of the front channel bars. To adjust the shelves within the supporting frame, the front bolts are removed, the shelf inclined until the pins 8 are withdrawn from the perforations 90 10 far enough to allow the shelf to be moved upward or downward, the shelf is moved, the pins 8 are inserted, the shelf leveled and the bolts 7 again inserted and their nuts 95 screwed up.

In order to brace the supporting frame of the shelving I may provide transverse braces

11 which extend from each rear channel bar to the other, being attached to the flanges 2''' by bolts 12 passing through perforations 12' in the flanges 2''', intermediate of 5 the perforations 10.

The top of the shelving is covered by a top plate 13 having a downwardly projecting rear flange 13' and the cornice-like front flange 13'' which is bolted to the front channel bars 2.

As seen in Fig. 2, when two or more units are to be combined, I use a common partition plate 3', which is bolted to the inwardly turned flanges 2' of both adjacent 15 units, the partition plate being located between said flanges of course. The whole series of units may be thus combined if desired to any extent required.

It will be obvious that in place of solid 20 partition plates 3 or 3', I might use bracing strips like the strips or braces 11. These are bolted to the end channel bars in the same manner as the end or partition plates 3, 3'.

25 It will be seen that my construction provides a very simply put together shelving structure composed of few elements readily put up and as easily taken down, and capable of combination with other elements so as 30 to produce shelving of any desired capacity. It will also be seen that it provides a unit section which may be readily combined with other unit sections to any number desired and that no change of structure occurs in 35 the combination of two or more of these sections, the united sections becoming a coherent and interlocked whole.

In addition to the advantages above stated, it will be seen particularly from the 40 section Fig. 2, that my construction by the use of channel bars and the back plates 4 having offset margins provides a series of vertically extending compartments within which the nuts of the connecting bolts are 45 contained, thus the interior of the locker is relatively attractive in appearance, the bolts are almost entirely concealed, and at the same time they do not interfere with the free movement of the shelves.

50 In order that the details of my construction may be clear, the section in Fig. 2 is on rather an exaggerated scale.

Having thus described my invention what I claim as new and desire to secure by Letters Patent is:

1. A metallic shelf-supporting structure having four upright channel bars at the corners of the structure with inwardly turned flanges, end plates bolted to the outer 60 flanges of the front and rear channel bars, plates connecting the rear channel bars to each other, and a shelf adjustably supported on said channel bars.

2. A metallic shelf-supporting structure

having four upright channel bars at the 65 corners thereof with inwardly turned flanges, the inside flanges being extended laterally parallel to the face of said channel bars, plates connecting the end channel bars with each other and bolted to the outside flanges, 70 plates connecting the rear channel bars to each other and bolted to the rear face thereof, and adjustable shelves supported by said channel bars.

3. A metallic shelf-supporting structure 75 having upright channel bars at the corners of the structure, the flanges of said bars being turned inward, one of said flanges on each bar being extended laterally toward the middle of the set of shelving, end plates 80 bolted to the outer flanges of the end channel bars, a back plate bolted to the face of the rear channel bars, said back plate having laterally offset margins opposed to the inwardly turned lateral flanges of each of the 85 rear channel bars, and a series of shelves supported within said structure having supporting pins passing through said channel bars, but removable therefrom.

4. A metallic shelf-supporting structure 90 having four upright channel bars at the corners thereof, each provided with inwardly turned flanges one of which flanges on each bar is laterally extended, end plates bolted to the outer flanges of the channel bars, a 95 back plate having offset margins bolted to the faces of the rear channel bars, braces connecting the rear channel bars to each other and bolted to the laterally extended flanges of said rear channel bars, and a series of shelves each shelf supported with bolts and pins adapted to enter perforations in the laterally extended flanges of said channel bars and to be supported thereon.

5. A metallic shelf-supporting structure 10 consisting of a series of unit sections, each unit section having four upright channel bars at the corners thereof, shelves supported within the four channel bars of each section and independently movable, end plates 11 attached to the extreme ends of the combined sections, and partition plates common to two sections located between and bolted to the adjacent channel bars of adjacent sections.

6. In a metallic shelf supporting structure, channel bars forming the uprights of the structure, each provided with inwardly turned flanges, one of which flanges on each bar is laterally extended and made with a 12 series of perforations therein, in combination with a series of shelves, each consisting of a plate having downwardly extending flanges at the edges thereof, said flanges being perforated for the passage of supporting 12 pins or bolts.

7. In a metallic shelf-supporting structure, a series of uprights formed by channel bars,

back plates having offset margins and shelving arranged within said supporting structure, the said plates and channel bars being so arranged as to provide vertical compartments through the walls of which the connecting bolts pass.

5 In testimony whereof I have signed my

name to this specification in the presence of two subscribing witnesses.

RICHARD W. JEFFERIS.
